STABILIZED BRIEF CASE

Lewis Lifton, New York, N. Y.

Application December 30, 1948, Serial No. 68,159

2 Claims. (Cl. 150—1.6)

1

This invention is a new and improved brief case of the type having reinforced pivotally associated complementary outer and inner frames desirably fastened to the spaced outer panels thereof and to the intervening expandable and contractible gusset connected to the panels. Where the brief case is closed these pivoted frames telescope and generally are in a vertical relation and closed but when the brief case is opened the pivoted inner ends of the frames swing upwardly to widely separate the latter and thus constitute a larger opening for conveniently inserting articles within the case. For conveniently carrying a brief case of the type alluded to resort is had to a swingable handle which is attached to the reach of the outside pivoted frame. Thus in carrying the brief case, an upward thrust due to the load is applied to the outer frame causing appreciable vertical separation between the reaches of the closed frames apart from unevenly distributing the load. One object of the invention deals with keeper means connected to the reach of the upper or outside hinged frame having channel shaped means for removably receiving the cooperating reach of the lower or inside frame to prevent separation of the upper reach away from the lower reach in the closed relation of the frames concomitantly absorbing a part of the intensity or weight of the load, thereby more effectively distributing the load on the companion pivoted frames for stabilizing purposes. Another important object is realized in the provision of serviceable protective shoes fixedly straddling spaced bottom portions of the brief case to prevent wear and marring thereof. Other important objects, and functional and structural features of the invention will appear from the following detailed description considered in the light of the accompanying drawings wherein:

Fig. 1 is a perspective view of the brief case according to my invention.

Fig. 2 is a transverse sectional view of Fig. 1 but showing the brief case fully opened.

Fig. 3 is a plan view of Fig. 2.

Fig. 4 is a perspective view of one of the protective shoes.

Fig. 5 is a perspective view of the stabilizing keeper.

Fig. 6 is an enlarged transverse sectional view on the line 6—6 of Fig. 1, and

Fig. 7 is a detailed and sectional view of a shoe attached to a bottom portion of the brief case and taken on the line 7—7 of Fig. 1.

Representative of the embodiment disclosed, the brief case 10 is characterized by the front and

2

rear leather panels or walls 11 and 12 effectively interconnected by an expandable and contractible leather gusset 13 fixedly carrying spaced partitions 14 and 15 for dividing the interior of the brief case into several compartments.

Appropriately fastened to the upper margins of the front and rear panels 11 and 12 and to the gusset 13 are the covered U-shaped inner or lower and outer or upper frames 16 and 17 having their inner ends effectively pivoted on the suitably retained fulcrum pins 20.

Straddling and fixedly secured by rivets 21 is the U or channel shaped upper component 22 of the keeper K having a lower U-shaped component 23 merging with and depending from the reversely curved component 22.

Component 23 is characterized by the slightly diverging walls 24 and 25 for straddling and removably receiving the lower or inside covered swingable frame 16 when the frames are closed. Specifically component 23 conveniently receives and retains reach 26 of the lower frame 16 for absorbing a part of the load on the reach 27 when the brief case is lifted and suspended from the swingable handle H carried by reach 27. By such retaining action of the load absorbing component 23, the upper reach 27 is prevented from lifting away from the lower reach 26, thereby effectively sealing the frames in their collapsed or closed relation.

To prevent needless wear on the bottom part of the brief case protective metal shoes as S are fastened to spaced lower marginal portions of the panels 11 and 12 and contiguous spaced portions 35 of the gusset 13. These shoes are also fastened to spaced portions of the lower folds F of the gusset.

Each shoe S constitutes a U-shaped member having its concavity facing upwardly and defined by the upstanding spaced sides 30 and 31 which in fact form ears straddling adjacent lower marginal portions of the brief case and which are fastened to the latter by suitable rivets 33. The bottom wall of each shoe is concavo-convex in formation as shown and is adapted to effectively rest on a suitable supporting surface while the inside ends engage the lower parts of the brief case.

Tongue or flap T is secured to rear panel 12 and 50 to the covering for the upper swingable frame 17 and carries at its lower end a hasp H detachably latched by the locking means L. In the closed and locked relation of tongue T (Fig. 1) the latter conceals keeper K. On closing of the brief case, component or bight 23 of the keeper telescopically

but removably receives and retains the covered lower reach 26 as previously stated to hold the reaches 26 and 27 together for more effectively dividing the weight of the load.

Various changes may be made in details of construction and arrangement of parts without departing from the spirit of the invention or sacrificing any of the advantages thereof inherent therein.

I claim:

1. In a brief case, spaced panels, a gusset interposed between said panels and secured thereto, upper and lower U-shaped telescoping frames secured to the upper margins of said panels and gusset and embodying upper and lower reaches and including depending side portions having their lower ends pivotally connected, and a one-piece keeper having an upper U-shaped component defining a relatively deep channel facing rearwardly for receiving substantially the entire width of said upper reach and including an oppositely facing depending lower U-shaped component integral with and disposed closely under said upper reach and in part extending rearwardly and appreciably beyond said lower component and having an upper downwardly and rearwardly uninterrupted member common to said upper component and including a downwardly and forwardly sloping lower member diverging away from said upper member and defining therewith a rearwardly contracted forwardly facing channel for removably and in part closely receiving said lower reach on closing of said frames to prevent vertical separation of said lower reach away from said upper reach.

2. In a brief case having lower juxtaposed marginal portions, spaced shoes to prevent wear

on said portions and each comprising a one-piece hollow member including a lower wall and upstanding but transversely spaced ears defining with said lower wall an upwardly facing channel for closely receiving said marginal portions, said bottom wall being both longitudinally and transversely curved to characterize an outwardly convex surface and an inner concaved surface at the bottom of said channel, said wall having ends at an elevation higher than the remaining intermediate portions thereof for supporting said marginal portions and for maintaining parts of said marginal portions between said ends spaced from said intermediate portions of said wall, and rivet means for anchoring said ears to said marginal portions.

LEWIS LIFTON.
